UNITED STATES PATENT OFFICE

2,438,825

SELECTOR

Bert W. Roth, Riverdale, N. Y., assignor to Trans-Lux Corporation, New York, N. Y., a corporation of Delaware

Application June 16, 1945, Serial No. 599,857

9 Claims. (Cl. 250—41.5)

1

This invention relates to a structurally and functionally improved selector and in its more specific aspects aims to provide a unit of this character presenting a structure alternative to that disclosed in my prior application for United States patent on Controller, filed July 27, 1944, and identified under the Serial Number 546,884.

It is a primary object of the invention to furnish a mechanism of this character and which will require but minimum power to operate. Accordingly, the demands in this connection may be reduced to a minimum. Therefore, if a standard mechanism is employed as the basic operating unit of an assembly such as is taught herein, the usual motive force incorporated in this unit will suffice to cause a functioning of the controller.

This is aside from the fact that wear of the parts will be reduced to a minimum. Also, with small power requirements, noise of operation will likewise be reduced, thus avoiding annoyances in this connection.

An additional object is that of furnishing a selector structure in which the number of parts will be reduced to a material extent. Accordingly, production costs will be reduced and an extremely efficient and compact machine may be designed.

Another object is that of furnishing a unit of this type which will be extremely positive in its functioning. Therefore, errors attributable to the operation of the mechanism will be reduced to a minimum, aside from the fact that service requirements will also be reduced.

With these and other objects in mind, reference is had to the attached sheet of drawings illustrating one practical embodiment of the invention, in which:

Fig. 1 is a sectional plan view diagrammatically showing a layout of apparatus; and

Fig. 2 is a sectional side view thereof.

A primary operating mechanism such as preferably forms a part of the present unit may be of the nature shown in the prior United States patent to Kleinschmidt, 1,448,750, of March 20, 1923, or Noxon et al., 2,252,232, of August 12, 1941. Reference is herein had to disclosures such as are embodied in these patents in order that the complete controller unit herein contemplated may be visualized. This is especially true in view of the fact that, with a view to avoiding unnecessary illustration, the structures shown in these patents have not been included in the present drawings except in a very general manner.

Thus, in the drawings, the reference numeral

5 indicates selector bars. The reference numeral 6 indicates the shift mechanism which forms a part of units as illustrated in the afore mentioned patents. No attempt has been made to illustrate 5 the code bars, magnets, selector bars, drop-in bars, etc., etc., and by means of which a perforated tape associated with the transmitter causes a predetermined operation of the conventional mechanism. Suffice it to say that any desired form of such mechanism may be employed and by means of which, in response to electrical impulses usually transmitted by wire, a certain selected bar or equivalent unit is caused to shift.

If a number of examples of the manner in 15 which the mechanism of the present invention may be associated with the mechanism of a more or less standard unit are to be visualized in detail, reference is had to my earlier application in which such illustration is made. Likewise, as 20 disclosed in that application, as well as in the Unkles et al. Patent 2,843,594, dated March 7, 1944, and entitled "Sign control and system," an apparatus is described, the operations of which may be governed by a control mechanism such 25 as is embraced in the present invention. At the same time, it will be understood that other mechanisms might likewise be governed by this controller. Therefore, except where otherwise indicated in the appended claims, such a particular 30 combination is to be regarded in an illustrative rather than in a limiting sense.

Preferably, however, bars 7, functioning as actuating or "letter, character or numeral bars" are embodied as part of the apparatus. These 35 bars are shifted as bars 5 are moved. There being twenty-six letters in the alphabet, it is preferred that twenty-six bars 7 be employed. Certain of these bars will perform a dual function as herein-after brought out. This will be in order that, 40 for example, ten reference numerals and certain characters may be provided for. These additional symbols of indicia may obviously be accommodated without having each of the bars 7 of a dual nature. Therefore, by providing 45 twenty-six bars 7, a more than adequate number of elements is furnished to provide for all of the letters of the alphabet, numerals, and symbols which may in any given instance be necessary.

Preferably, the actuating bars are arranged in 50 a vertically extending bank. Supports 8 and 9 may define opposite ends of this bank. It is intended that, contrary to the teachings embodied in my prior application, the desired functional results are not achieved in the present controller 55 by the actuating bars directly throwing switches.

Rather, it is proposed that these actuating bars serve to establish or interrupt light rays which are directed against light sensitive units such as photo-electric cells. Thus, depending upon whether these cells are energized or de-energized (according to the particular hook-up of an apparatus) units such as the elements of a setting head as identified in the heretofore referred to Unkles et al patent may be actuated. In view of the fact that in that patent thirty-five elements are provided as a unit or group of contacts, the present controller has been shown as embodying a series of controls harmonious or related in number to such elements. As will be appreciated, this is merely for the purpose of illustrating a practical embodiment and a greater or lesser number of controls or units might be embodied.

Thus, the numeral 10 indicates photo-electric cells. In order to avoid unnecessary expense and complication, only thirty-five of such cells are provided. Light rays may pass to the individual cells either through a tube 11 or a branch tube 12. The latter being conveniently offset, it is provided with a reflector 13 serving to divert light rays to the light-sensitive unit 10. This reflector, which may take any desired form, has been indicated by the reference numeral 13. The support 9 may be provided with apertures 14 in line with the tubes 11 and 12 respectively and through which light rays may pass.

The opposite support 8 is conveniently provided with mounting elements (not shown) which serve to carry suitable lens elements 15. These elements correspond in number to the number of tubes 11 and 12 and are so arranged as to direct light rays into the apertures 14 when the space between the supports 8 and 9 is unobstructed. Conveniently beyond the supports 8, sources of illumination are mounted. These preferably include neon tubes 16 and 16' beyond which reflectors 17 are disposed.

Each of the actuating bars 7 carries shutters 18. These may be in the form of transversely extending blades or arms. The shutters on each of the bars are disposed in certain predetermined permutations. Accordingly, when a given bar is actuated, light rays from one or the other source 16 and 16' will be obstructed in their passage toward the aperture 14 or else be free to enter such apertures according to the design of the apparatus. In the present layout of the controller, it is intended that with light rays passing to the photo-cells 10, no operation of the elements or units connected to the latter will occur. This will happen only when such light rays are interrupted. As is obvious, however, instead of securing operation by de-energizing the light-sensitive cells or elements, the lay-out might be re-designed so that the desired results would be achieved by energizing the cells.

As diagrammatically indicated, each of the cells 10 is connected by separate leads 19 to units to be controlled. Included in these units are amplifying devices as, for example, thyratron tubes and transformers. In view of the fact that elements of this type are well known, it is unnecessary to illustrate them. The sources of illumination are connected by leads 20 with a source of current supply 21. A switch 22 is connected to the shift mechanism 6. This switch is coupled to the leads 20 so that, according to its position, one or the other of the tubes is energized by the source 21. Again, it is intended that the light rays passing through the tubes 12 may control, for example, the creation of indicia symbols. The

light rays passing through the tubes 11 may control the formation of letters. The shutters or blades 18 extending from one or both faces of each of the actuating bars 7 will be arranged accordingly. As will be apparent by an alternative arrangement, the light rays passing through the tubes 11 might provide for numerals and symbols while the light rays passing through tubes 12 might provide for the letters. Also, in the event

10 that the controller is not connected to a sign unit similar in function to that described in the Unkles et al. patent, other desirable circuits might be included in or arranged beyond the selector mechanism of the present invention.

15 With a layout of apparatus such as the present, it will be apparent that with the bars 5 or their equivalents operating to periodically elevate or shift one of the actuating bars 7, the light-sensitive units or cells 10 will be energized or de-energized. This will occur, of course, only with respect to selected cells and according to the permutations of light-obstructing elements or blades 18 associated with any given bar. As afore brought out and with the parts in a condition of rest, light rays will be free to pass from the particular tube which has been energized through to all of the elements 10. The energization of the particular tube will depend upon the position of the switch mechanism 6 controlling 20 the switch 22. Assuming the latter to be in a certain position, then the elevation or other movement of the particular actuating bar 7 will cause the light rays to selected photocells to be interrupted. Therefore, the circuits extending from those cells will be affected and the mechanisms connected to these circuits will in turn be caused to operate. With the return of the actuating bar to its normal position, the light rays will again be free to pass through to the 25 entire bank of photo-cells 10. The actuation of a subsequent bar will cause a different permutation of photo-cells to be affected by the interruption of the passage of light rays thereto. Again, a desired functioning of the mechanisms 30 connected to the circuits will follow. If, now, a shift occurs, the switch 22 will be moved. This will result in a de-energization of the tube which has heretofore been energized and an energization of the second tube. Thereupon, a movement 35 of selected actuated bars 7 will provide for different permutations of photo-cells to be affected. With twenty-six bars 7 employed and each one of them being of a dual nature, fifty-two different permutations are feasible. As afore brought out, 40 however, normally only certain of the bars will be of a dual nature (i. e., with shutters or blades 18 extending to both sides of them) and therefore only a lesser number of permutations will be necessary or achieved.

45 60 Thus, among others, the several objects of the invention as specifically afore noted are accomplished. Obviously, numerous changes in construction and rearrangements of the parts might be resorted to without departing from the spirit 65 of the invention as defined by the claims.

I claim:

1. A selector including in combination a series 70 of light-sensitive elements, a source of light arranged to act on said elements, a plurality of actuating members mounted for reciprocation, and different permutations of units fixedly associated with said members and movable to interrupt and permit the passage of light rays to said elements.

2. A selector including in combination a series 75 of light-sensitive elements, a source of light ar-

ranged to act on said elements, a plurality of actuating members mounted for reciprocation, two series of units fixedly associated with certain of said members, each of said series being arranged in a different predetermined permutation, and means for reciprocating said actuating members to render either of said series operative to interrupt and permit the passage of light rays to said elements.

3. A selector including in combination a series of light-sensitive elements, a source of light arranged to act on said elements, a plurality of actuating members mounted for reciprocation, two series of units fixedly associated with certain of said members, each of said series being arranged in a different predetermined permutation, and means for reciprocating said actuating members to render either of said series operative to interrupt and permit the passage of light rays to said elements upon the actuating member carrying the same being moved; said light-sensitive elements being in excess of the number to the number of units associated with an actuating member.

4. A selector including in combination a series of reciprocating actuating members, permutations of light-obscuring units associated with at least certain of said members, a series of light-sensitive elements, means defining a light path past one permutation of units and towards said elements, means defining a second light path past a second permutation of said units, and means for directing light rays down one only of said paths.

5. A selector including in combination a series of actuating members, permutations of light-obscuring units fixedly associated with at least certain of said members, a series of light-sensitive elements, means defining a light path past one permutation of units and towards said elements, means defining a second light path past a second permutation of said units, means for directing light rays down one of said paths, and shift means for selecting the path to be followed by said light rays.

6. A selector including in combination a series of actuating members, permutations of light-obscuring units associated with at least certain of said members, a series of light-sensitive elements, means defining a light path past one permutation of units and towards said elements, means defining a second light path past a second permutation of said units, a pair of light sources, one for each of said paths, and a switchable switch connected to said light source to alternately energize one only of the same.

7. A selector including in combination a single group of light-sensitive elements, said elements being connectable to the units of a controller to create, by means of the mechanism of the latter, indicia such as numerals and letters, actuating members mounted for reciprocation, two groups of light-obstructing means fixedly carried by at least certain of said actuating members and providing for the creation of either of said types of indicia, a source of illumination beyond said actuating members and directed towards said light-sensitive elements, and means whereby said single group of elements may respond to movement of either of the groups of light-obstructing means associated with any given actuating member.

8. A selector including in combination a row of light-sensitive elements, actuating members mounted for reciprocatory movements in advance of and to one side of said elements, permutations of light-obscuring units mounted one by each of said members, and the permutations of said units on different members differing from each other, a source of illumination arranged beyond said units and directed towards said elements, and means for reciprocating said members.

9. A selector including in combination a row of light-sensitive elements, actuating members mounted for reciprocatory movements in advance of and to one side of said elements, permutations of light-obscuring units mounted one by each of said members, and the permutations of said units on different members differing from each other, a source of illumination arranged beyond said units and directed towards said elements, means for reciprocating said members, further permutations of light-obscuring units mounted by and extending from certain of said members, and means whereby light from said source may be obstructed by said further group of obscuring units.
